UNITED STATES PATENT OFFICE.

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY.

MARKING MACHINE.

Application filed March 20, 1925. Serial No. 17,119.

This invention relates to marking machines and more particularly to such machines in which there is an operator-controlled setting device to enable the ready 5 interchange of the markers.

Marking machines are extensively used in shoe factories for marking the various portions of the upper and for this purpose are usually provided with a plurality of adjustable markers in the form of rotatable disks arranged side by side which may carry the printing type faces directly upon their toothed peripheries or may be mechanically connected to other wheels which do carry 10 the type faces. When thus used, the row of characters imprinted commonly is arranged to indicate such things as the case number, the style of shoe, the size, width, etc. While marking machines of the same type are used 15 for many other purposes and to impress a great variety of characters, the example noted will serve for the discussion of the present invention, although it will be understood that the invention is not limited to any 20 particular use or to the illustrated marking organization.

Such machines frequently require the re-setting of the markers between every operation and, to enable the operator to set the 25 marker carrying rotatable disks or other members without bringing the hands into direct contact therewith, setting devices have commonly been provided having operating handles. To enable the easy use of such a setting device it is common to provide locking means restraining all but one of the 30 markers in order that the operator may not disturb markers which it is desired not to change.

In view of the foregoing, an object of the 35 present invention is to provide a marking machine organization having improved type retaining and setting devices by the use of which the release and adjustment of one or more selected markers may be still further facilitated.

Looking toward the fulfillment of this 40 object and in accordance with a feature of the invention, the illustrated machine has a setting device carried by a sliding frame which is supported for positioning movement transversely of a marking head carrying a plurality of adjustable markers mounted side by side. In the illustrated arrangement the adjustable markers are in the form

of toothed disks provided with type faces formed upon the ends of the teeth on their peripheries, and the disks are mounted for rotation on a cylindrical support and are provided with notches on their inner peripheries. A notched locking bar is mounted in the sliding frame in engagement with the notches of the various disks so that all the disks save the one which is opposite to the notch in said bar are locked against rotation. 60 A manually operated setting device having a star wheel is mounted on said frame in corresponding relation to the notch of the locking bar and preferably an index device is provided upon the frame to indicate quickly 65 to the operator both the particular disk with which the setting device is in co-operative relation and the type face on said disk which is in printing position.

Still another feature of the invention consists in the provision of means in addition to the setting devices referred to by which markers which require especially frequent adjustment may be readily released and reset independently of the other markers. In the 70 illustrated machine a novel setting device is arranged to control two particular disks designed for use in shoe work to print size and half-size marks. Such an arrangement is particularly desirable because of the necessity of changing the size disks more often than the other disks are changed and in the 75 illustrated arrangement an independent setting device is arranged in engagement with these two disks arranged to move them 80 together step by step to print the whole succession of size and half-size numbers or 85 separately if desired. Because of much greater use of these particular disks they are so mounted that they are independent of the locking bar which controls the other disks 90 of the marking head.

This and other features of the invention will be more readily understood from a consideration of the following specification 95 taken in connection with the accompanying drawings, in which:

Fig. 1 is a side elevation of one form of marking machine to which a marking head provided with my improved setting device 100 has been applied;

Fig. 2 is a transverse vertical section through the marking head on the line 2-2 of Fig. 1;

Fig. 3 is a diagrammatic perspective show- 110

ing typical rotatable disks and the associated setting devices; and

Fig. 4 is a fragmentary perspective of part of the locking bar.

In the machine to which my invention has been illustratively applied an automatically adjustable work-supporting table 10 is slidably mounted in a guide 12 formed in a bracket attached to a frame 14 of the machine. A locking arm 16 holds the table against vertical movement when the machine is at rest. The marking mechanism is carried for up-and-down movement in an oscillating head or support 20 comprising laterally spaced hangers 22 and 24 which are pivoted at 26 upon a bifurcated bell crank lever 28 to which power may be supplied to move the marking head into engagement with and away from the work. The support 20 is guided for movement in parallel planes by means of a parallel arm 30 pivoted in the machine frame at 32 and pivotally attached to the upper end of the support 20 at 34. An inking roll 36 is arranged to carry ink from an inking-supply roll 38 to the type faces and this inking roll is carried on the end of an arm 40 pivotally mounted in the frame of the machine and actuated by a link 42 from an extension 44 on the parallel arm 30. A rod 46 connected to the bell crank lever 28 passes through the end of the table-locking arm 16 which is normally held in locking position by means of a spring 48 surrounding the rod 46. As the head is carried into marking position, however, the enlarged end 50 of the rod 46 raises the table-locking arm 16 and allows automatic adjustment of the table under the tension of a spring 52 and the pressure of the marking head upon the work carried by the table so that said pressure is uniform regardless of the number of layers of work carried thereby.

The marking head is supported between the spaced side hangers 22 and 24 by means of a cylindrical support 50 carried by said hangers and made hollow to reduce its weight. This hollow support 50 has a pair of internal enlargements one of which is provided with a suitable recess 53 for the reception of an electrically heated cartridge unit 54. A guideway 56 is provided in the other enlargement and is located in the periphery of the cylindrical support for a purpose to be later explained. Rotatably mounted upon the support are a plurality of adjustable markers in the form of annular disks 60, which, in the present instance, are provided with toothed peripheries having type faces upon the ends of the teeth. Each of these disks is provided upon its inner periphery with a plurality of notches 62 for the reception of a locking bar 64 slidably mounted in the guideway 56 extending longitudinally of the external

periphery of the cylindrical support. As will be noted from Fig. 4 the locking bar is provided with a notch 66 which, in the present instance, is shown as being of the width of one of the disks. By means of this arrangement all but one of the disks is held in locked position upon the support while the particular disk which is opposite to the notch 66 on the bar 64 may be turned to bring the desired type face into printing position. The locking bar 64 forms part of a sliding frame made up with lateral members 68 and 70 which are joined at the front by a transverse bar 72 carrying an index finger 73 which is positioned opposite the notch 66 of the bar 64 and thus indicates to the operator which disk is released for adjustment. At the rear of the frame a rod 74 is pivotally mounted in the frame and passes through bosses upon the hangers 22 and 24, a fragment of one of these being indicated at 76 in Fig. 3. A setting device is provided upon this rod 74 and secured thereto, which, in the present instance, takes the form of a star wheel 80 arranged for engagement with the teeth of any one of the disks in the head. Whether or not the index finger 73 is used, the position of this star wheel 80 indicates visually to the operator that disk which is released and may be set, because it is positioned upon the rod 74 directly opposite to the notch 66 of the bar 64. An operating handle 82 is provided to allow the rotation of the disk which is opposite to the notch 66 by rotating the star wheel 80. As will be seen from Fig. 2, a ball latch 84 is provided in the side member 70 of the sliding frame and this latch is adapted to engage suitable recesses 86 (Fig. 3) in a head 88 carried at the other end of the rod 74. This latch is intended to hold the star wheel 80 impositively in the position in which the corresponding marker disk has one of its type faces in alignment with the row of types to be impressed on the work.

When a marking machine of this type is used for shoe work, it commonly will be provided with a pair of disks 106 and 110 having type faces to indicate sizes on one of the disks 110 and half sizes upon the other disk 106. These disks have enough type faces on their peripheries so that, when they are moved together step by step, they may be caused to print the whole succession of size and half-size numbers. In the illustrated arrangement a setting wheel 90 carried upon a rod 92 pivoted in the hangers 22 and 24 is arranged at a point intermediate between two such disks so that it engages both of the disks and turns them together when manipulated by means of an operating handle 94. Because of the much greater use of these particular disks, they are made independent of the locking bar 64 by making them freely

rotatable upon a ring 96 which is notched upon its inner periphery to allow passage of the locking bar 64, this ring 96 being carried in a fixed position upon the cylindrical support 50. At the end of the rod 92 carrying the setting wheel 90 is a head 98 provided with suitable recesses 100 which are adapted to be engaged by the rounded end of a plunger 102 pressed outwardly by means of a 10 spring 104. This latching arrangement serves a similar purpose as does the latch 84 but it also performs additional functions. When it is desired to move the setting wheel 90 to the right to bring it into engagement 15 with only the half-size disk 106, the operator is able to move the rod 92 carrying this setting wheel to the right against the tension of the retaining spring 104 by grasping the operating handle 94. To this end sufficient clearance is provided between the head 20 98 and a boss 108 upon the hanger 22 in which the latch is mounted. When, on the other hand, the operator desires to turn only the size wheel 110, the setting wheel 90 may 25 be moved to the left after a notched spacing lever 112 pivoted upon the hanger 24 and provided with a forwardly extending handle has been lifted to allow the operating handle 94 to approach more closely the side of the 30 hanger 24. The tension of the spring 104, acting through the plunger latch 102, will then be sufficient to move the setting wheel 90 into alignment with the size disk 110.

In the operation of the setting devices 35 the size disks will be controlled by turning the operating handle 94 while the other disks will be controlled, to bring the desired markers into operative position, by sliding the frame carrying the locking bar 64 laterally until the index finger 73 is positioned in alignment with the particular disk which it is desired to change. The operating handle 82 may then be rotated to set this disk, which, it will be remembered, is released 40 because of the coincidence therewith of the notch 66 upon the bar 64.

The operation of the machine is controlled by means of a suitable clutch (not shown) under the control of which the head-carrying support 20 is moved up and down to bring the lowermost row of type faces upon the marking head into and out of engagement with the work carried upon the work table 10. As the marking head starts on its 55 downward movement, the inking roll 36 will be carried across the row of type faces together with any type upon a name plate 120, if such a plate is being used, and during the continued movement of the marking head the inking roll will be brought into engagement with the ink-supplying roll 38 while the markers are engaging the work upon the table. As the marking head returns again to its upper position, the inking 60 roll will return to the position shown in Fig.

1 and supply ink to the type faces. The operation of the automatic work-supporting table 10 is well understood in the art. When the marking head is depressed, locking device 16 is released just prior to the engagement of the work by the marking head so that the table is pressed against the under side of the work under the tension of a spring 52 with the result that the pressure of the marking head upon the work is substantially uniform regardless of the number of pieces of work carried by the table. As soon as the marking head starts upward, the locking device 16 is again brought into engagement with the shank of the table 10 75 and held there by tension of the spring 48.

Having described the invention, what I claim as new and desire to secure by Letters Patent of the United States is:

1. In a marking machine, hangers, a cylindrical support carried in said hangers, a plurality of disks rotatably mounted upon said support and each provided with a plurality of notches in their inner peripheries, said cylindrical support being provided with a guideway, a frame slidably mounted in said hangers for movement transversely thereof, a setting device rotatably mounted in said frame and adapted to be brought into engagement with the desired disk, a locking device carried in said frame slidably supported in the guideway of said support and adapted to engage the notches of and lock all the disks save the disk which is in engagement with the setting device, and a bar upon said frame provided with an indicating device located adjacent to the peripheries of the disks to indicate the disk with which the setting device is in engagement.

2. In a marking machine, a cylindrical support provided with a guideway adjacent to its periphery, a notched locking bar mounted in said guideway, a plurality of disks rotatably mounted upon said support and provided with notches in their inner peripheries adapted to receive said locking bar, a notched ring mounted upon said support adjacent to said disks, and an additional disk freely rotatable upon said ring.

3. In a marking machine, a support, a notched locking bar slidably mounted on said support, a plurality of disks rotatably mounted upon said support provided with notches in their inner peripheries adapted to receive said locking bar, a setting device movable with said locking bar to cooperate with the disk which is rendered free for rotation by the position of the notch in said bar, and a latch co-operating with said setting device arranged to indicate the extent of angular movement necessary to bring the disk exactly to printing position.

4. In a marking machine, a pair of adjustable markers provided with a succession of type faces, a setting device normally posi-

tioned and arranged to adjust simultaneously both of said markers, and a spring retaining means allowing displacement of said setting device to a position where it will engage only one of said markers.

5. In a marking machine, a support, a pair of markers adjustably mounted on said support and provided with a succession of type faces, a setting device associated with said markers normally positioned for engagement with both of said markers to move them together, a spring urging said setting device into position for engagement with only one of the markers, and displaceable means resisting the action of said spring.

10. In a marking machine, spaced hangers, a cylindrical support carried by said hangers, disks rotatably mounted upon said cylindrical support, a setting wheel carried upon a rod passing through said hangers, an operating handle for said setting wheel, and a spring urging said setting wheel rod laterally in one direction.

15. In a marking machine, spaced hangers, a cylindrical support carried by said hangers, disks rotatably mounted upon said cylindrical support, a setting wheel carried upon a rod passing through said hangers, an operating handle for said setting wheel, a spring urging said setting wheel rod laterally in one direction, and displaceable means resisting the action of said spring.

20. In a marking machine, side hangers, a cylindrical support fixed in said hangers and having a guideway groove lengthwise of its external periphery, a plurality of annular disks rotatably mounted upon said support, each of said disks being provided with a plurality of notches around its inner periphery adjacent to the cylindrical support, a locking 25 bar longer than said cylindrical support and having a narrow notch on its outer edge, said bar being mounted in said guideway groove to position the notch in the bar opposite a selected disk and to cause the bar to enter the notches of and to lock all the other disks, and a setting device arranged to engage the outer peripheries of the disks, mounted for lateral positioning movement

50 with said notched bar and arranged to engage the disk not locked by the bar and to turn the latter disk while the other disks remain locked.

9. In a marking machine, hangers, a cylindrical support carried in said hangers, a plurality of annular disks rotatably mounted upon said support and each provided with a plurality of notches around its inner periphery, the external periphery of said cylindrical support having a guideway parallel 60 to the axis of the support, an open frame slidably mounted in said hangers for movement transversely thereof, a setting device rotatably mounted in said frame and adapted to be brought into engagement with any selected disk, and a locking bar with a narrow notch, said bar rigidly interconnecting the sides of the frame and being slidably supported in the guideway of said support to position the notch in the bar opposite said selected disk and to cause the bar to enter the notches of and to lock all the other disks.

10. In a marking machine, an oscillating head, a hollow cylindrical support mounted in fixed position in said head and provided with two internal enlargements, a plurality of disks rotatably mounted on said support and provided with notches in their inner peripheries, one of the enlargements of said 75 hollow support being provided with a recess for supporting and retaining a heating unit, said support being provided with a guideway extending lengthwise of its outer periphery adjacent to the other enlargement, a notched bar in said guideway mounted for movement with respect to said support and adapted to enter the notches of all but one of the disks thereby to lock said disks against rotation upon the support, and external means movable with said notched bar and located thereby opposite to that one of the disks which is not locked, said external means being adapted to indicate visually that the disk to which it is opposite is not locked.

90 In testimony whereof I have signed my name to this specification.

PERLEY R. GLASS.
